US00D810165S

(12) **United States Design Patent** (10) Patent No.: **US D810,165 S**
(45) Date of Patent: **** Feb. 13, 2018**

(54) **MULTIMEDIA TERMINAL**

(71) Applicant: **Samsung Electronics Co., Ltd.**, Gyeonggi-do (KR)

(72) Inventors: **Bill Webb**, San Francisco, CA (US); **Chris Harsacky**, San Francisco, CA (US); **Shweta Grampurohit**, San Jose, CA (US); **Mohammad Tanabian**, San Jose, CA (US); **Robert Christensen**, Belmont, CA (US); **Dion Isselhardt**, Saratoga, CA (US); **Chunkwok Lee**, Santa Clara, CA (US)

(73) Assignee: **Samsung Electronics Co., Ltd.**, Suwon-si (KR)

(**) Term: **15 Years**

(21) Appl. No.: **29/555,117**

(22) Filed: **Feb. 18, 2016**

(51) LOC (11) Cl. **15-99**
(52) U.S. Cl. **D15/199**

(58) **Field of Classification Search**

USPC D13/180; D14/124, 125, 126, 129, 133, D14/314, 317, 336, 348-351, 356, 420; D15/199; D16/200, 201, 202, 203, D16/205-221, 225, 232, 235; D21/576, D21/577, 578; D26/2, 40
CPC G03B 15/03; G03B 19/04; H04N 5/2251-5/2254

See application file for complete search history.

(57) **CLAIM**

The ornamental design for a multimedia terminal device, as shown and described.

DESCRIPTION

FIG. 1 is a perspective view of a multimedia terminal;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof.

The broken lines shown in the drawings illustrate portions of the multimedia terminal that form no part of the claimed design.

1 Claim, 3 Drawing Sheets
